FISHING RIG

Samuel L. Popeil, Chicago, Ill., assignor to Popeil
Brothers, Inc., Chicago, Ill.

Filed Dec. 4, 1972, Ser. No. 312,222

Term of patent 14 years

Int. Cl. D22—05

U.S. Cl. D22—26

FIG.2

FIG.7

FIG.8

FIG.9

FIG.10

FIG.11

FIG.12

FIG.13

FIG.14

FIG. 1 is a front perspective of a fishing rig.
 FIG. 2 is a side elevational view of the fishing rig.
 FIG. 3 is a top plan view.

FIG. 4 is a side elevational view.

FIG. 5 is a bottom view.

FIG. 6 is a front view.

FIG. 7 is a rear view.

FIG. 8 is a front quarter perspective view of the subject fishing rig in the same scale and from the same vantage point as FIG. 1, but showing the rod in the retracted position.

FIG. 9 is a view corresponding to FIG. 2, but with the rod in the retracted position.

FIG. 10 is a view corresponding to FIG. 3, with the rod in the retracted position.

FIG. 11 is a view corresponding to FIG. 4 with the rod in the retracted position.

FIG. 12 is a view corresponding to FIG. 5 with the rod in the retracted position.

FIG. 13 is a view corresponding to FIG. 6 with the rod in the retracted position.

FIG. 14 is a view corresponding to FIG. 7 with the rod in the retracted position.

I claim:

The ornamental design for a fishing rig, as shown.
